DESIGN FOR A SET OF TOY ANIMAL BLOCKS

Eoina Nudelman, Chicago, Ill.

Application August 30, 1944, Serial No. 115,129

Term of patent 7 years

(Cl. D34—15)

To all whom it may concern:

Be it known that I, Eoina Nudelman, a citizen of France, residing at Chicago, in the county of Cook and State of Illinois, have invented a new, original, and ornamental Design for Sets of Toy Animal Blocks, of which the following is a specification, reference being had to the accompanying drawings, forming part thereof.

Fig. 1 is a top plan view of a set of toy animal blocks, showing my new design;

Fig. 2 is a bottom plan view; and

Fig. 3 is an edge view of one of the blocks shown in Figs. 1 and 2, all being of the same thickness.

I claim:

The ornamental design for a set of toy animal blocks, as shown and described.

EODNA NUDELMAN.
